UNITED STATES PATENT OFFICE.

EWALD KRUSIUS, OF WEST HOBOKEN, NEW JERSEY.

DESIGN FOR A RAZOR-HANDLE.

41,342.

Specification for Design.

Patented May 2, 1911.

Application filed November 28, 1910. Serial No. 594,614. Term of patent 7 years.

To all whom it may concern:

Be it known that I, EWALD KRUSIUS, a citizen of the United States, residing at West Hoboken, in the county of Hudson and State of New Jersey, have invented a new, original, and ornamental Design for a Razor-Handle, of which the following is a specification, reference being had to the accompanying drawing, forming part thereof.

The figure is a side elevation of a razor handle showing my design.

I claim:

The ornamental design for a razor handle as shown.

EWALD KRUSIUS.

Witnesses:

THEO. G. HOSTER,
PHILIP D. ROLLHAUS.
